COUCH OR SIMILAR ARTICLE

David L. Rowland, 49 W. 55th St.,
New York, N.Y. 10019

Filed Dec. 30, 1969, Ser. No. 20,710

Term of patent 14 years

Int. Cl. D6—02

U.S. Cl. D6—63

FIG. 1

FIG. 3

FIG. 2

FIG. 4

FIG. 5

FIG. 6

FIG. 1 is a front perspective view of a couch or similar article showing my new design but broken in the middle; the side panels and back are upholstered and there is an upholstered front rail;

FIG. 2 is a rear perspective view of the couch or similar article of FIG. 1, also broken in the middle;

FIG. 3 is a view in side elevation of the couch or similar article of FIG. 1;

FIG. 4 is a front elevational view of a modified form of couch or similar article showing my new design, broken in the middle, with the side panels and back not upholstered and not having an exposed front panel;

FIG. 5 is a rear elevational view of the couch or similar article of FIG. 4, also broken in the middle;

FIG. 6 is a front perspective view of another modified form of couch or similar article showing my new design and also broken in the middle; the side panels and back

are not upholstered and there is a non-upholstered front panel below the seat cushion.

I claim:

The ornamental design for a couch or similar article, substantially as shown and described.
